UNITED STATES PATENT OFFICE.

CLAYTON A. DUNHAM, OF GLENCOE, ILLINOIS, ASSIGNOR TO YOUNG PUMP COMPANY, OF CHICAGO, ILLINOIS, A CORPORATION OF INDIANA.

MULTIPLE-JET EXHAUSTER.

Application filed December 26, 1925. Serial No. 77,895.

This invention relates to an improved multiple jet exhauster, especially adapted for use in heating systems.

In some heating systems, a continuously circulating liquid stream, or "hurling circuit", is employed, which is drawn from a receiving tank and forced through a vacuum-producing chamber in the form of a jet, the liquid stream then being returned to the tank. Return fluids from the heating system are drawn into the vacuum chamber by the reduced pressure, and entrained by the liquid stream and carried into the receiving tank.

The present invention relates to an improved form of jet exhauster for use in such a system, and comprises means for projecting a plurality of separate jets into and through the vacuum chamber, the jets cooperating with one another to more efficiently withdraw and collect the return fluids from the heating system.

The general object of this invention is to increase the efficiency of jet exhausters, using liquid for the actuating fluid, that is, to reduce the quantity of actuating liquid required per unit of fluid mixture exhausted and to permit operation with the actuating liquid at high temperatures as well as at low, and the reduction of the power consumption required to furnish the liquid at the pressure required for actuating the jet. In this improved exhauster, the stream of actuating liquid supplying the jet is broken up into a number of streams and each stream into small particles during its passage across the suction space, thereby providing for entrainment of the fluid being exhausted with the actuating liquid so that the actuating liquid serves as a multiplicity of small pistons, while preserving the contractive action of the jet when the liquid is at atmospheric or approximately atmospheric temperatures. This provides a maximum actuating liquid surface passing through the suction area per unit of time, but with the use of a minimum volume of actuating liquid.

Another object of the invention is to control the expansive action of the actuating liquid, when hot, within the nozzle from which the jet is discharged, so as to permit conversion of a portion of the heat energy into kinetic energy applied to the liquid particles, as a result of the expansive action.

The above objects are attained by the use of a multiplicity of actuating nozzles, and by properly shaping the liquid passages in these nozzles.

Other objects and advantages of the invention will be more apparent from the following detailed description of certain approved apparatus designed for putting into effect the principles of the invention.

In the accompanying drawings:

Fig. 1 is a side elevation of that portion of a heating system in which the exhauster is used.

Fig. 2 is an end view of the apparatus shown in Fig. 1, the pump-operating motor being omitted.

Fig. 3 is a side view of the complete exhauster, showing the inlet and outlet connections.

Fig. 4 is a central longitudinal section through the exhauster, taken substantially on the line 4-4 of Fig. 5.

Fig. 5 is a transverse section, taken substantially on line 5-5 of Fig. 3.

Fig. 6 is a transverse section, taken substantially on the line 6-6 of Fig. 3.

Fig. 7 is a longitudinal central section on an enlarged scale, through one of the improved nozzle and delivery-tube units.

Referring first to Figs. 1 and 2, we will briefly describe a typical heating system in which this improved exhauster may be used. The receiving tank 1 is adapted to hold a quantity of water, or actuating liquid, which is withdrawn near the bottom of the tank, through pipe connection 2 by a pump 3 driven by the electric motor 4 or any other suitable driving means. The liquid is forced by pump 3 through the pipe 5 and inlet connection 6 to the vacuum chamber 7, through which chamber the liquid is discharged under pressure as a jet, or plurality of jets, which are received in the outlet connection 8 and pass back into the upper end of tank 1. This continuous, forced circulation of water from and back to the tank 1, through the exhauster 7, is known as the hurling circuit. The return fluids from the heating system are conducted through pipe 9, check-valve 9', and a strainer 10 into the vacuum chamber 7, through inlet opening 11 (see Figs. 4 and 5). These return fluids are entrained by the liquid jets, as described more in detail hereinafter, and are carried through pipe connection 8 into the receiving tank 1. A liquid

discharge pipe 12, leading from the inlet connection 6, is controlled by a valve 13, which is normally closed so that all of the liquid withdrawn from tank 1 by pump 3 will be forced through the hurling circuit. A suitable valve is provided in the upper portion of tank 1 to discharge the gases returned from the heating system, but the returned liquid will gradually augment the supply in tank 1 until the rising water level in the tank raises the float 14 (see dotted lines, Fig. 2), and through the link and lever connections 15 open the valve 13 to permit the discharge of liquid through the pipe 12. When the liquid supply in tank 1 has been sufficiently diminished, the float 14 will sink and again close the outlet valve 13. Systems of the type just briefly described are well known, the particular object of the present invention being to provide an improved exhauster, positioned in the casing 7, for more efficiently accomplishing the withdrawal of the return fluids into the receiving tank 1. Obviously, the improved exhauster now about to be described, is capable of use for other purposes, and in other systems than that here shown, which has been described merely by way of example.

The casing member 7, enclosing the so-called "vacuum chamber", has a flanged extension 16 at one side adapted to connect with the strainer 10, the returned fluids flowing into the vacuum chamber through passage 11. The ends of the casing 7 are in the form of flat flanged plates 17 and 18, having respectively a plurality of inlet and outlet openings 19 and 20 in alignment with one another. The liquid inlet connection 6 is flanged at one end 21 to connect with the pump outlet, and is flanged at the other end 22 to connect with the end plate 17 of casing 7. End plate 22 is provided with a plurality of discharge openings 23 adapted to align with the openings 19 in the end of casing 7 to form continuous passages from the inlet connection 6 to the chamber in casing 7. Each nozzle 24 has an exterior annular flange 25 at its inlet end adapted to fit an enlargement in inlet opening 19, the nozzles being clamped in place by the end plate 22 of inlet connection 6. This is a convenient means for anchoring the nozzles in place in the casing 7, but other means, such as a screw threaded connection might be used. The outlet or discharge connection 8 is flanged at one end 26 to connect with the end plate 18 of casing 7, the end 26 being provided with a plurality of openings 27 adapted to align with the passages 20 in end plate 18. The delivery tubes 28 have outer flanges or collars 29 adapted to fit enlarged portions of the openings 20, whereby the delivery tubes will be clamped securely in place against endwise movement when the end plates 18 and 26 are assembled and secured together.

In the construction here shown, the other end of outlet connection 8 is turned at right angles, as at 30, and flanged, as at 31, to connect with the upper end of tank 1. Of course, this portion of the device may be varied to suit the installation in which the exhauster is used.

Referring now more particularly to Fig. 7, each nozzle 24 encloses a fluid passage, the inlet portion 32 of which is cylindrical and of sufficient size to make the pressure loss negligible in this portion of the nozzle. At 33 the diameter of the passage is gradually diminished until it reaches its minimum at the restricted throat 34, the passage then flaring at 35 out to the somewhat enlarged discharge opening 36. The flare between throat 34 and the delivery or discharge opening 36 is proportioned according to the expansive action desired which in turn is governed by the temperature of the actuating liquid, the degree of expansion desired, and the physical properties of the actuating liquid. Since the water in tank 1 is derived from condensed steam, it will have a rather high temperature, and this temperature may even be above the boiling point at the reduced pressure existing in the exhausting chamber into which the jets discharge. The flared portion 35 of the improved discharge nozzle permits the liquid to expand or partially vaporize, and lower its temperature, the heat being transferred into kinetic energy and utilized in the exhausting process. Any considerable vaporization of the actuating fluid is thus avoided, and at the same time the efficiency of the jet is increased. When the usual converging nozzle is used, a scattering or flaring of the jet is caused by the increased internal pressure, and the decreased external pressure when the jet emerges into the low pressure exhausting chamber. This is avoided by the expanded or diverging nozzle 35, which materially decreases the internal pressure of the jet. The added kinetic energy derived from the heat released by this preliminary expansion of the jet serves to project the water particles across the expanding chamber with considerable force in a substantially straight stream, which will be entirely received within the delivery tube 38.

The delivery tube 28 has a flared inlet opening 37 which diminishes in diameter toward the cylindrical passage 38. This passage 38 is gradually increased in diameter or flared out, at 39, until it reaches the outlet 40 where the liquid is discharged into the outlet pipe 8.

In operation, the liquid is forced under pressure by pump 3, into the inlet passage 32 of nozzle 24, and thence through the restricted throat 34, which projects the liquid in the form of a jet under high velocity through the intervening space in the

vacuum chamber toward the delivery tube 28. The flared discharge opening 35 beyond the throat 34 of the nozzle permits the liquid to expand so that the heat released 5 as a result of the pressure change within this portion of the nozzle is utilized to increase the kinetic energy of the water particles in the jet and reduce the temperature of the water. The jet will be projected 10 straight across the suction space in the form of a multiplicity of small liquid particles, which entrain portions of the returned fluids in the chamber 7 to carry these fluids with the liquid stream into the open end 37 of the 15 delivery tube 28. The bell-mouthed or flared entrance opening 37 of the delivery tube is to insure proper guidance of the jet of actuating liquid into the tube, and also provide increased area for the reception of 20 the fluids which are being exhausted from the chamber 7. The combined fluids pass through the passage 38 in tube 28 into the delivery pipe 8, the flared end 39 of the delivery tube serving to convert the kinetic 25 energy of the stream into pressure energy, facilitating the passage of the fluids through pipe 8.

In any liquid jet exhauster of this general type, when the actuating liquid stream 30 passes across the space intervening between the nozzle and the delivery tube, the fluids in the chamber of which this space is a part, will be withdrawn and taken away by the actuating fluid as a result of (1) the contraction of the jet, (2) the friction of the actuating liquid with the fluid contents of the chamber, and (3) by entrainment of the fluids being exhausted with the particles of the actuating liquid stream. The removal 35 of the fluids from the chamber will reduce the pressure therein and cause more of these return fluids to flow into the chamber 7 through pipe 9 and strainer 10. By using a plurality of nozzles, thus providing a plurality 40 of smaller actuating jets instead of one larger jet, the maximum actuating liquid surface passing through the suction area per unit of time, is provided with the use of a minimum volume of the actuating liquid. Thus a largely increased friction surface 45 is presented to the fluids being exhausted. The smaller stream of the jet, together with the peculiar conformation of the projecting nozzle, tends to break up the 50 actuating liquid into a multiplicity of small particles during its passage across the suction space, thereby increasing the entrainment of the fluids being exhausted between these liquid particles which serve as small 55 pistons. This does not interfere with the contractive action of the jet when the liquid is at atmospheric or approximately atmospheric temperatures.

Owing to the heat loss by radiation from 60 tank 1, the water in the hurling circuit,

which is projected through the nozzles, will ordinarily be at a lower temperature than the fluids returned from the heating system through pipe 9. Part of these returned fluids are usually in the form of vapor, and 70 the colder water in the jets will have a condensing action on this vapor, thus aiding the production of a vacuum in chamber 7. This exchange of heat from the vapors to the liquid of the jets is facilitated by the greatly 75 increased contacting area of the two fluids resulting from the use of a plurality of small jets instead of one larger jet.

These small nozzles may be made of a standard and most efficient size, and the size 80 or capacity of the exhauster can be varied as desired by simply using a larger or smaller vacuum or exhausting chamber, and increasing or diminishing the number of nozzles used therein. In the example illustrated, 85 six nozzles are used, but this number could be increased or diminished as desired without materially affecting the principles of operation of the exhauster. Although it is preferable to use a separate delivery tube 28 90 for each nozzle 24, as in the apparatus illustrated and described above, all of the nozzles might project their jets into a single delivery tube.

I claim:

1. A liquid actuated jet exhauster comprising a casing enclosing an exhausting chamber, the chamber having an inlet opening in one side for fluids, and having aligned inlet and outlet openings in its opposite ends, 100 a connection for delivering liquid to the exhausting chamber, said connection having a plurality of openings in its delivery end adapted to mate with the inlet openings in the casing, another connection for carrying away the liquid discharged from the outlet openings in the other end of the casings, said latter connection having a plurality of openings in its receiving end adapted to mate with the outlet openings 105 in the chamber, a plurality of nozzles mounted in the inlet openings and a plurality of delivery tubes mounted in the outlet openings, whereby the liquid is projected across the exhausting chamber in a 110 plurality of separate jets, each nozzle and delivery tube having an outstanding collar which is clamped between the abutting end walls of the casing and the inlet or outlet connection.

2. The method of withdrawing fluids from an exhausting chamber consisting in circulating a stream of liquid and projecting it as a jet through the chamber, the initial temperature of the liquid stream being 115 higher than the boiling point of the liquid at the pressure prevailing in the chamber, and expanding the stream before the jet is formed to reduce the temperature of the liquid below this boiling point.

3. The method of withdrawing fluids from an exhausting chamber consisting in circulating a stream of liquid and projecting it as a plurality of small jets through the chamber, the initial temperature of the liquid stream being higher than the boiling point of the liquid at the pressure prevailing in the chamber, and expanding the jets at their formation so as to reduce the temperature of the liquid below this boiling point.

4. In a vacuum pump system, in combination, a tank, a pipe circuit including a jet exhauster, means for forcing heated liquid from said tank through the circuit and back to the tank, and means for delivering fluids to said exhauster, the exhauster embodying means for dividing the liquid stream into a plurality of separate jets and for expanding each jet prior to its discharge through the exhauster.

5. In a vacuum pump system, in combination, a tank, a pipe circuit including a jet exhauster, means for forcing heated liquid from said tank through the circuit and back to the tank, and means for delivering fluids to said exhauster, the exhauster embodying a plurality of nozzles for projecting the liquid stream through the exhauster as a plurality of separate jets each nozzle having a flared discharge opening for permitting the liquid to expand prior to its discharge.

6. In a vacuum pump system, in combination, a tank, a pipe circuit including a jet exhauster, means for forcing heated liquid from said tank through the circuit and back to the tank, means for delivering fluids to said exhauster, the exhauster embodying a nozzle for projecting the liquid stream through the exhauster in the form of a jet, the nozzle having a flared discharge opening for permitting the liquid to expand prior to its discharge.

7. In a vacuum pump system, in combina-

tion, a tank, a jet exhauster, means for withdrawing liquid from the lower portion of the tank and forcing it up through the jet exhauster, and connections for delivering the liquid and exhausted gases from the upper portion of the exhauster to the upper portion of the tank, the exhauster embodying means for dividing the liquid stream into a plurality of separate jets and for expanding each jet prior to its discharge through the exhauster to reduce its temperature.

8. In a vacuum pump system, in combination, a tank, a jet exhauster, means for withdrawing liquid from the lower portion of the tank and forcing it up through the jet exhauster, and connections for delivering the liquid and exhausted gases from the upper portion of the exhauster to the upper portion of the tank, the exhauster embodying a plurality of nozzles for projecting the liquid upwardly through the exhauster in the form of a plurality of separate jets and for expanding each jet prior to its discharge through the exhauster to reduce its temperature.

9. In a vacuum pump system, in combination a tank, a pipe circuit including a jet exhauster, means for forcing heated liquid from said tank through the circuit and back to the tank, and means for delivering fluids to said exhauster, the exhauster embodying an exhausting chamber, means for projecting a jet through the chamber, and means for expanding the jet to reduce its temperature prior to its discharge through the chamber.

10. The method of withdrawing fluids from an exhausting chamber consisting in circulating a stream of highly heated liquid and projecting it as a jet through the chamber, and expanding the liquid stream before the jet is formed to reduce its temperature so that it will not vaporize while passing through the pressure exhausting chamber.

CLAYTON A. DUNHAM.
